(57) **CLAIM**

The ornamental design for a documenting process calibrator, as shown and described.

DESCRIPTION

FIG. 1 is a top front right perspective view of a documenting process calibrator showing our new design.

FIG. 2 is a bottom rear left perspective view thereof.

FIG. 3 is a front elevation view thereof.

FIG. 4 is a left side elevation view thereof.

FIG. 5 is a right side elevation view thereof.

FIG. 6 is a rear elevation view thereof.

FIG. 7 is a top plan view thereof.

FIG. 8 is a bottom plan view thereof.

FIG. 9 is a top front right perspective view of the documenting process calibrator of FIG. 1 with a rear stand shown in an extended position.

FIG. 10 is a bottom rear left perspective view thereof.

FIG. 11 is a front elevation view thereof.

FIG. 12 is a left side elevation view thereof.

FIG. 13 is a right side elevation view thereof.

FIG. 14 is a rear elevation view thereof.

FIG. 15 is a top plan view thereof; and,

FIG. 16 is a bottom plan view thereof.

The broken lines in the figures illustrate environment only and form no part of the claimed design.
